DOUGHNUT MACHINE

Stephen A. Gardner, Minneapolis, Minn., assignor
to Dough-King, Inc., Minneapolis, Minn., a
corporation of Minnesota

Application November 25, 1939, Serial No. 306,168

11 Claims. (Cl. 53—7)

My invention relates to doughnut machines and has for an object to provide a doughnut machine which will be extremely efficient in operation.

Another object of the invention resides in providing a doughnut machine in which the doughnuts are progressed along a channel by means of the flow of the cooking liquid and in which the number of doughnuts passing through the machine is positively and accurately controlled to control the degree of cooking of the doughnuts.

Another object of the invention resides in providing a doughnut machine in which the capacity of the machine may be manually varied at will.

A still further object of the invention resides in providing cams for operating the doughnut former and the control device of the doughnut machine and in providing a construction for varying the capacity of the machine whereby a single cam of fixed form can be used for each of said devices.

An object of the invention resides in providing each of the cams for operating the doughnut former and control device with a number of irregularities, each irregularity forming a doughnut and controlling the passage of a doughnut along the channel and in providing means for preventing certain of the irregularities from effecting the operation of the doughnut former and control device.

Another object of the invention resides in providing spring controlled means for urging the cam followers operating in conjunction with the said cams into engagement therewith and in providing means for periodically rendering said spring controlled means inoperative.

Another object of the invention resides in providing a shaft having engaging members thereon adapted to engage parts movable with the cam followers for preventing movement of the followers toward the cam surfaces of the cams, and in providing another cam adapted to be manually moved to engage or disengage a cam follower carried by said second shaft, whereby said engaging members are brought into operative or inoperative position at will.

Other objects of the invention reside in the novel combination and arrangement of parts and in the details of construction hereinafter illustrated and/or described.

In the drawings:

Fig. 1 is a plan view of a doughnut machine illustrating an embodiment of my invention.

Fig. 2 is a longitudinal elevational sectional

view taken on line 2—2 of Fig. 1 and drawn to a greater scale.

Fig. 3 is a view similar to Fig. 2 showing the parts in altered position.

Fig. 4 is a plan sectional view taken on line 4—4 of Fig. 2.

Fig. 5 is an inverted plan sectional view taken on line 5—5 of Fig. 2.

Fig. 6 is an elevational sectional view taken on line 6—6 of Fig. 4.

This invention is an improvement of the doughnut machine invented by Alexander S. T. Lagaard, Serial Number 302,945 filed Nov. 6, 1939, and the construction of parts not shown in detail in this application may be had from the application of said Alexander S. T. Lagaard.

In the drawings I have shown a doughnut machine A which consists of a case 10 constructed with end walls 11 and 12 and side walls 13 and 14 connected therewith. The case includes uprights 15 at the corners of the same which extend throughout the height of the case and to which the various walls are attached. The walls are preferably constructed of sheet metal and are directly secured to the uprights 15. The case 10 further includes upper and lower frames 17 which are channel shaped in cross section and which extend perimetrical about the case and hold the various uprights 15 in position. The walls of the case are also attached to these frames.

Within the case 10 is disposed a cooking kettle 18 which is preferably of cast metal and which is constructed with a bottom 19 and with vertical walls 21 extending upwardly therefrom. The vertical walls are connected at their upper ends with upper walls 22 and the various walls and bottom are so arranged as to form a channel 23 which extends throughout the major portion of the kettle and which provides a way along which the doughnuts may travel. The kettle 18 has one corner of the same removed, as designated at 24, leaving a main portion 25 of the width of the case 10 and of a length equal to about two-thirds of the length of the same. This construction provides an extension 26 to the kettle which extends up to the end wall 12. The case 10 is constructed with a ledge 27 extending about the margin of the same. A guard 29 on the case 10 issues upwardly from the walls thereof and overlies the edge of the ledge 27. The kettle 18 is supported on the frame 17 in any suitable manner.

The channel 23 is arranged to provide a straight run 32 which starts in close proximity to wall 12 and follows along wall 13. Channel 23

55 55

at the end of run 32 makes a curve 33 which leads into another straight run 34 following along the wall 11. At the end of this run the channel has another curve 35 which leads into still another straight run 36 which follows along the wall 14. At the end of the run 36 the channel is constructed with a loop 37 which is connected to another straight run 38. The run 38 terminates in a curve 39 which, in turn, is connected to a short straight run 41 parallel with the run 34 and closely positioned relative thereto. This run is connected to a curve 42 which, in turn, is connected to a straight run 43 parallel with the run 32 and disposed in close proximity thereto. The run 43 discharges into a reservoir 44 which is merely an enlargement of the said run. From this reservoir a short run 45 is provided which is connected by a curve 46 with the end of the run 32.

20 The major portion 25, of kettle 18, is enclosed by means of a hood 47. This hood utilizes the uprights 15 at the end wall 11 and two other uprights 48 which are attached to the case 10 at the locality of the end of the major portion 25 of the kettle formed by the corner 24. Between the various uprights are provided glass panels 49 which are slidably supported in guides 51 whereby the said panels may be removed. The hood 47 includes a top by means of which the major portion 25 of kettle 18 is enclosed and which has not been shown in the drawings.

25 In the reservoir 44 is provided a vertical tubular duct 52 which communicates at its lower end with the bottom of the reservoir 44. In this duct 35 is disposed a propeller or elevator 53 which is mounted on the armature shaft of a motor 54. The duct 52 communicates at its upper end with the run 45 of the channel 23, thus discharging the cooking liquid from the reservoir 44 and into 40 the run 45 of the channel, from which it flows throughout the course of the channel and is returned into the reservoir.

30 Situated at the beginning of the run 32 of channel 23 is a doughnut former 55 which comprises a receptacle 56 for dough and a cutter 57 connected therewith. Such construction being well known in the art will not be described in detail in this application. The cutter 57 includes a flanged sleeve 58 which severs dough extrusions from the mass contained in the receptacle 56. This sleeve is reciprocated in a vertical direction by means of a forked arm 59 which is mounted on a rock shaft 61. Rock shaft 61 is journaled at one end in a bearing 62 and at its other end in a manner to be presently more fully described. 35 The forked arm 59 swings freely on the shaft 61 but may be locked in relation thereto by means of clutch 60 constructed as follows: Rigidly secured to the shaft 61 is an arm 63. This arm has a retractable pin 64 which may engage the forked arm 59 and cause the arm 63 and arm 59 to travel in unison. Air pressure is provided in the upper portion of the receptacle 56 which forces the dough downwardly through the cutter 65 and as the sleeve 58 is reciprocated, annular dough extrusions are deposited in the cooking liquid in the beginning of the run 32 of channel 23.

30 In the run 36 of channel 23 is arranged a twisted tubular turner 65. This turner inverts the doughnuts after the same have been cooked a predetermined time so that the doughnuts may be cooked equally on both sides. Such construction being well known in the art will not be described in detail in this application. It is to be

noted, however, that the turner 65 inclines in the direction of flow of the cooking liquid so that the bottom 19 of the kettle 18 at the run 41 is considerably lower than at the run 34.

35 In the run 43 of channel 23 is disposed an ejector 66 for removing the cooked doughnuts from the cooking liquid. This ejector comprises a shaft 67 which is constantly driven in a manner to be presently described in detail. This shaft has mounted on it oppositely extending cranks 10 68 and 69. Sets of toothed blades 71 and 72 are mounted on the said cranks and are adapted to be alternately raised and lowered and also moved in a longitudinal direction as the shaft 67 rotates. The lower ends of these blades slide upon 15 an inclined rest 73 which is mounted on the bottom 19 of kettle 18 in the portion of the run 43 leading from the curve 42. It will readily be comprehended that, as the doughnuts reach the said blades the doughnuts are elevated and progressed upwardly and outwardly of the kettle 18. The ejector 66 is disposed within a trough 74 constructed with two side plates 75 and 76 and a bottom 77 connected therewith. The said trough extends outwardly beyond the wall 12 of 25 the case 10 and directs the doughnuts out of the machine.

20 For controlling the rate of travel of the doughnuts along the channel 23, two control devices 78 and 79 are employed. These control devices 30 operate to allow the doughnuts, one at a time to enter the turner 65 and the ejector 66, whereby the degree of cooking of the doughnuts on both sides may be controlled. The control device 78 is situated in the run 34 of channel 23, while 35 the control device 79 is situated in the run 41 of channel 23.

25 Inasmuch as the control devices 78 and 79 do not form any feature of the instant application for patent the said devices have not been shown 40 in detail in the drawings and the same will not be described, reference being had to the above noted application for patent of Alexander S. T. Lagaard for the construction of the said device. It will be noted, however, that the control device 45 78 is operated by a shaft 112 and that the control device 78 is operated from the control device 78 through a shaft 134. It may be mentioned that the control devices operate periodically. In operation each device is rapidly lowered and moved beneath a doughnut blocked thereby and subsequently raised and slowly moved back toward the original position to allow the doughnuts, one at a time, to pass the said device. This is accomplished through a single 55 revolution of the shaft 112 which is driven as will be subsequently more fully described.

30 In order to procure sufficient cooking time for the doughnuts in advance of each of the said control devices when the machine is first started, it becomes necessary to prevent travel of the doughnuts until the desired number of doughnuts are in the machine. In conjunction with the control device 78 an obstructing member 291 is employed which is adapted to be moved in the path of movement of the doughnuts and to obstruct travel of the same. This device is operated by a rod 299 slidable in the guide 301 attached to the ledge 27 of kettle 18. A knob 302 on the rod 299 permits of operating the said obstructing member to move the same into obstructing or clearing position.

35 In conjunction with the control device 79 a similar obstructing member 304 is employed which is operated by rod 308 guided for move- 75

ment in a guide 309 attached to ledge 27. This rod is operable through a knob 311 attached to the same.

The cutter 55, the ejector 66, and the two control devices 78 and 79 are all operated by an operating mechanism 140 contained within a chamber 167 formed within a case 144, disposed in the cut-away corner 24 of the kettle 18. This operating mechanism will now be described in detail.

10 The case 144 includes a lateral wall structure indicated in its entirety by the reference numeral 145 which is open at the top and bottom. This wall structure includes two side walls 146 and 147 and two end walls 148 and 149. These walls 15 are covered at the top by a cover 151 which is secured to said walls by means of counter-sunk screws 152 threaded into bosses 153 formed on said walls. In a similar manner a closure 154 is provided for the lowermost portion of the case 20 144, which closure is attached to the wall structure 145 by means of screws 155 which are similarly threaded into bosses 156 formed on the wall structure 145. The case 144 is provided with pads 157 formed on the closure 154, which pads 25 rest upon the upper frame 17 and are secured thereto by means of screws 158 which pass through the uppermost flanges of the frame members of frame 17 and are threaded into said pads.

30 The closure 154 of case 144 has attached to the underside thereof an electric motor 159 having a vertical shaft 161. Motor 159 is constructed with an end bell 162 provided with a flange 163 adapted to engage a ring 164 cast on the under surface of the closure 154. Screws 165 extending through the flange 163 are threaded into the ring 164 and hold the motor 159 attached to the closure 154. Motor 159 may be of any desirable construction and the details thereof have not been shown in the drawings. The shaft 161 of motor 159 passes through a seal 166 and into the chamber 167 formed within the case 144.

Issuing from the wall 147 of case 144 are two bearing supports 168 and 169. The bearing support 168 has attached to it a bearing 171 for the lower end of a vertically extending shaft 172. This shaft is journalled in its upper end in a ball bearing 173 which serves as an end thrust bearing for restraining longitudinal movement of the shaft 172. Shaft 172 has secured to the lower end thereof a spur gear 174 which meshes with a pinion 175 fast on the shaft 161 of motor 159. Shaft 172 also has formed on it a worm 176 which meshes with a worm wheel 177 keyed to a horizontally extending shaft 178. Shaft 178 extends completely across the case and is journalled in bearings 181 and 182 carried by the end walls 148 and 149.

60 The ejector 66 is driven from the shaft 172 in the following manner: Shaft 67 of the said ejector extends through a tubular housing 183 provided with a flange 184 at one end. This flange is secured to the wall 149 of case 144 by means of screws 185. The housing 183 is provided at its outer end with a bearing 186 which journals one end of the shaft 67. The other end of this shaft extends into the chamber 167 of case 144 and is journalled in a bearing 187 issuing outwardly from the wall 147 of case 144. The shaft 67 has mounted on it a spiral gear 188 which meshes with another spiral gear 189 fast on the shaft 172. These gears are so proportioned that the shaft 67 travels at a suitable speed to alternately raise the toothed blades 71 and 72 and procure ejection of the doughnuts.

The mechanism for operating the control devices 78 and 79 will now be described in detail. Shaft 112 extends along the upper portion of the kettle 18 toward the operating mechanism 140 contained within the case 144 and is connected by means of a coupling 211 with a shaft 212. Shaft 212, as best shown in Fig. 2, extends through the wall 146 of case 144 and into the chamber 167 of the said case at an elevation near the closure 154 thereof. Within the chamber 167 of the case 144 is formed an elongated boss 213 which is provided with bearings 214 and 220 journaling the shaft 212. This shaft has secured to the end of it a bevel gear 215 which meshes with another bevel gear 216 fast on a shaft 217 extending horizontally across the case 144. The latter shaft is journalled in bearings 218 carried by the side walls 148 and 149 of the case 144 and shown in Fig. 5.

Attached to the wall 148 of case 144, near the uppermost portion of the same, as best shown in Fig. 6, is a stud 219. Mounted for oscillation on this stud is a lever 221 which has a depending arm 222. Arm 222 is formed with a gear segment 223 which meshes with a pinion 224 rotatably mounted on the shaft 217. The lever 221 is further formed with an arm 225 which carries at the end of it a roller 226 adapted to engage the surface 227 of a disc cam 228. Cam 228 is keyed to the shaft 178 and is best shown in Fig. 6.

30 The lever 221 is urged to move in a counter-clockwise direction, as viewed in Fig. 6, to cause the roller 226 to bear against the cam 228 by means of the following construction: Issuing inwardly from the wall 147 of case 144 is a boss 231 which is bored at 232 to slidably receive a tubular spring housing 233. Tubular spring housing 233 has connected to the end of it a socketed head 234 which has secured to it a forked arm 235. Arm 235 is pivoted by means of a pintle 236 to the arm 222 of lever 221. Within the interior of the housing 233 is mounted a compression coil spring 237 which is seated at one end against the head 234. A plug 245 is screwed into the boss 223 and engages the other end of the spring 237. It will be readily comprehended that the spring 237 urges the roller 226 to follow the surface 227 of cam 228. In the event that the spring 237 should break, plug 245 may be removed from the exterior of the device and the spring may be removed from the housing 233. A new spring may then be inserted and the plug 245 screwed into the boss 231.

The construction for procuring operation of the shaft 212 which operates the two control devices 78 and 79 of the invention is best shown in Fig. 5. The gear 224, which was previously referred to, has issuing outwardly from it a flange 247. This flange is constructed with a ratchet notch 248 in the face thereof. Adjacent to the flange 247, on shaft 217, is a head 249 which is keyed to the said shaft and which is constructed with a groove 251 in the same extending in a radial direction. In this groove is disposed a pawl 252 which is pivoted on a pin 253 extending through the head 249. The pawl 252 is adapted to engage the notch 248 in flange 247, and when the gear 224 is rotated in one direction, the head 249 and the shaft 217 are both rotated in the same direction. This causes rotation of shaft 212 and shaft 112 through the bevel gears 215 and 216 which operates the control devices 78 and 79.

75 The pawl 252 is yieldingly held in engagement with the notch 248 by means of a compression

coil spring 254 which is disposed in a bore 255 in the end of the shaft 217. This spring is seated against a plug 256, threaded in the end of the said shaft and engages a sliding plunger 257 in the bore 255 which bears against a finger 258 formed on the pawl 252, which finger extends through a slot 259 in the shaft 217 and into the bore 255. In this manner the pawl is held in engagement with the ratchet notch 248. By unloosening the plug 256, which is accessible through a removable cap 261, on the exterior of the wall 148 of case 144, spring 254 may be replaced when the occasion requires it.

The two control devices 78 and 79 operate only in one direction. To prevent reverse movement of these devices the head 249 is held from rotation when the gear 224 travels in the reverse direction. This is accomplished as follows: Formed on the interior of the wall 146 of case 144 is a threaded boss 262. This boss has screwed into it a tubular guide 263 formed with a bore 264. A plunger 265 is slidably in another bore 266 forming a continuation of the bore 264 and of reduced diameter. This plunger is constructed with a head 267 disposed within the bore 264. A compression coil spring 268 in the bore 264 engages the head 267 and urges the plunger 265 outwardly. The spring 268 reacts against a plug 269 screwed in the end of the tubular guide 263. The plunger 265 serves as a dog and is adapted to engage in a ratchet notch 271 formed in the outer periphery of the head 249. The two notches 271 and 248 are so arranged that rotation of the gear 224 in opposite directions causes rotation of the shaft 212 in one direction only.

For rocking the shaft 61 which operates the cutter 55, the following construction is used. Shaft 61 is connected by means of a coupling 191 with another shaft 192 extending across the walls 148 and 149 of case 144. This latter shaft is journaled in bearings 193 and 194 carried by the walls 148 and 149 of the case. The shaft 192 has keyed to it a bell crank 195 (Fig. 3) which has an upwardly extending arm 196 and a substantially horizontally extending arm 197. The arm 197 of bell crank 195 has rotatably mounted at the end thereof a roller 198 which is adapted to engage the periphery 199 of a disc cam 201. Cam 201 is constructed with a hub 202, Fig. 4, which is keyed to the shaft 178. The surface 199 of cam 201 is formed with two indentations 204 and 205 diametrically opposed which, when the roller 198 drops into the same, permit the bell crank 195 to oscillate, whereby the cutter sleeve 58 is raised and lowered to procure the deposit of dough formations into the cooking liquid in the kettle 18. The roller 198 is urged into engagement with the surface 199 of cam 201 by means of a spring similar to that described in connection with the mechanism for operating the control devices. This spring is contained within a tubular housing 206 slidable in a boss 207 issuing from the wall 147 of case 144. The said spring acts against a head 208 which is pivoted to the end of the arm 196 of bell crank 195 by means of a pin 210 and urges the same to cause a clockwise movement of shaft 192, as viewed in Fig. 3.

It will be noted that the cam 201, which operates the cutter 55, has two depressions 204 and 205 in it, whereby two doughnuts are cut for each revolution of the shaft 178. Likewise, the cam 228 which operates the control devices 78 and 79 has two depressions 212 and 213 in it by

means of which the control devices are operated twice for each revolution of the shaft 178.

By means of the construction now to be described, and which constitutes the instant invention, operation of the cutter and control devices may be procured through one only of the depressions of the two cams referred to. Extending across the walls 148 and 149 of the housing 144 is a shaft 91. This shaft is journaled in two bearings 92 and 93 carried by the walls 148 and 149 of the case 144. The shaft 91 has secured to it two arms 94 and 95, best shown in Fig. 4, which extend beneath the two spring housings 233 and 206. Each of these spring housings has a lug 96 welded or brazed thereto which is constructed with a face 97 facing in the direction of the two cams 228 and 201. The arms 94 and 95 are constructed with hooks 98 which, when the shaft is rocked, are adapted to engage the surfaces 97 of the lugs 96 and to restrain movement of the springs within the same. This holds the two cam followers 226 and 198 from engagement with the respective cams 228 and 201 and prevents the said cam followers from following the depressions in said cams while the spring housings are so engaged.

The shaft 91 is urged into the position shown in Fig. 6 by means of a spring 99, similar to the spring 231, which spring is contained in a spring housing 101 attached to the wall 147 of case 144, which is best shown in Fig. 3. This spring engages a plunger 102 slidable in the housing 101 and is pivoted to an arm 103 keyed on shaft 91. Arm 103 has a stop 104 on the same which engages wall 147 and limits the movement of shaft 91 to its position in which the arms 94 and 95 are situated, as shown in Fig. 2.

The shaft 91 is rocked in its bearings in the following manner: Attached to the said shaft is an arm 103 which is provided with a cam follower in the form of a roller 106 at the end thereof. This roller is adapted to engage a cam 107 slidably mounted on the shaft 178. Cam 107 has a pin 281 secured to it which passes through a hole 282 in the cam 201, (Fig. 4). By means of this construction the cam 107 is keyed relative to the shaft 178 and may move axially with respect thereto. The cam 107 is shifted longitudinally by means of the following construction: Extending downwardly from the cover 151 is a boss 284 which is drilled to form a bearing for a shaft 285, best shown in Fig. 3. Shaft 285 extends outwardly beyond the cover and has secured to it a finger piece 286 by means of which the said shaft may be rotated. Shaft 285 also extends below the boss 284 and has secured to its lower end an arm 287. This arm has attached to the end of it a pin 288 which engages within a groove 289 in the hub 275 formed on cam 107. When the shaft 285 is rotated, through engagement with the finger piece 286, pin 288 shifts the hub 275 along the shaft 178. This moves the cam 107 in a position to be engaged by the roller 106 or to a position free therefrom. The cam 107 has a depression 108 in it which, when the roller 106 is opposite, said depression withdraws the two hooks 98 from engagement with the lugs 96. This allows the cutter 55 and the two control devices 78 and 79 to operate once for each revolution of the shaft 178. When the roller 106 engages the raised portion of the cam 107, which is indicated at 109, the cutter and control devices are restrained from movement.

The operation of the invention is as follows: The channel 23 in kettle 18 is first filled with

cooking liquid. This liquid is maintained at a suitable temperature for cooking by means of a heater disposed beneath said kettle and which has not been shown in the drawings. The motor

- 5 54 is then started which causes operation of the propeller 53. Circulation of the cooking liquid in the channel 23 now commences. The motor 159 is now energized and the shaft 178 of the transmission mechanism set in operation. This procures operation of the ejector 66 and the two control devices 78 and 79. In addition, the shaft 61 is periodically oscillated. The clutch 60 is, however, maintained open so that the cutter 55 is normally inoperative. The container 56 is filled 10 with dough and air pressure applied to the same. As soon as the clutch 60 is closed the cutter 55 operates and dough extrusions are deposited in the flowing cooking liquid within the channel 23. The obstructing members 304 and 291 are moved 15 into obstructing positions by means of the knobs 311 and 392. As the doughnuts travel along the runs 32 and 33 of the channel 23 member 291 arrests the movement thereof and the said member is maintained in obstructing position until 20 the required number of doughnuts have accumulated in advance of the same. Thereafter the said obstructing member 291 is elevated and the doughnuts now travel through the control device 78 and are released, one at a time, to the turner 25 65. The doughnuts passing through the said turner are now arrested by means of the obstructing member 304 and the same stack up in advance of the control device 79. When a sufficient number of doughnuts have accumulated in advance of the obstructing member 304 the same 30 is elevated by knob 311 and the machine then continues to operate in its normal manner. As the doughnuts are released one at a time by the control device 79 the same pass up the ejector 66 and are discharged from the machine. When 35 it becomes desirable to change the capacity of the machine the same may be readily accomplished by shifting the finger piece 286. This brings the cam 107 into engagement with the roller 106. The hooks 98 are now periodically brought into engagement with the lugs 96 and one operation of the cutter and control device per revolution of the shaft 178 are procured instead of two as is the case when the cam 107 is 40 out of engagement with roller 106. In this manner either the maximum number or one-half as many doughnuts may be cooked in a unit of time.

The advantages of my invention are manifest. My improved doughnut machine is extremely positive in action. The operating mechanism of my invention is extremely simple and eliminates the use of auxiliary cams in conjunction with the main cam.

Changes in the specific form of my invention, as herein disclosed, may be made within the scope of what is claimed without departing from the spirit of my invention.

Having described my invention, what I claim as new and desire to protect by Letters Patent is:

1. In a doughnut machine in which the doughnuts are progressed along a way, a doughnut former for depositing dough formations in the cooking liquid in the way, a drive shaft, a cam 45 on the drive shaft, said cam having a plurality of irregularities, means controlled by said cam for operating said doughnut former and including a follower adapted to engage said cam, said follower causing an operation of the doughnut former when passing each irregularity, and means

for periodically engaging a part movable with said follower to restrain engagement of the follower with certain of said irregularities.

2. In a doughnut machine in which the doughnuts are progressed along a way, a doughnut former for depositing dough formations in the cooking liquid in the way, a drive shaft, a cam on the drive shaft, said cam having a plurality of irregularities, means controlled by said cam for operating said doughnut former and including a follower adapted to engage said cam, said follower causing an operation of the doughnut former when passing each irregularity, resilient means for urging said follower into engagement with said cam, and means for periodically engaging a part movable with said follower to restrain engagement of the follower with certain of the irregularities and against the action of said resilient means.

3. In a doughnut machine in which the doughnuts are progressed along a way, a doughnut former for depositing dough formations in the cooking liquid in the way, a drive shaft, a cam on the drive shaft, said cam having a plurality of depressions, means controlled by said cam for operating said doughnut former and including a follower adapted to engage said cam, said follower causing an operation of the doughnut former when entering into each of said depressions, resilient means for urging said follower into engagement with the cam, and means for periodically engaging a part movable with said follower to restrain entry of the follower into certain of the depressions and against the action of said resilient means.

4. In a doughnut machine in which the doughnuts are progressed along a way, a doughnut former for depositing dough formations in the cooking liquid in the way, a drive shaft, a cam on the drive shaft, said cam having a plurality of irregularities, means controlled by said cam for operating said doughnut former and including a follower adapted to engage said cam, said follower causing an operation of the doughnut former when passing each irregularity, and latching means for engaging a part movable with said follower to prevent movement thereof while the follower is in the position to engage one of said irregularities.

5. In a doughnut machine in which the doughnuts are progressed along a way, a doughnut former for depositing dough formations in the cooking liquid in the way, a drive shaft, a cam on the drive shaft, said cam having a plurality of irregularities, means controlled by said cam for operating said doughnut former and including a follower adapted to engage said cam, said follower causing an operation of the doughnut former when passing each irregularity, means engaging a part movable with said follower to restrain movement of the follower and engagement of the follower with the surface of said cam, and means operated by said shaft for periodically rendering said last named means operable to restrain movement of the follower when the follower is in position to engage certain of said irregularities.

6. In a doughnut machine in which the doughnuts are progressed along a way, a doughnut former for depositing dough formations in the cooking liquid in the way, a drive shaft, a cam on the drive shaft, said cam having a plurality of irregularities, means controlled by said cam for operating said doughnut former and including a follower adapted to engage said cam, said

follower causing an operation of the doughnut former when passing each irregularity, a spring for urging said follower into engagement with the surface of said cam, a housing for said spring connected to said follower, latching means for periodically engaging said housing to restrain movement of said follower by said spring when the follower is in position to engage certain of said irregularities, a cam operated by said shaft, and means operated by said cam for actuating said latching means.

7. In a doughnut machine in which the doughnuts are progressed along a way, a doughnut former for depositing dough formations in the cooking liquid in the way, a drive shaft, a cam on the drive shaft, said cam having a plurality of irregularities, means controlled by said cam for operating said doughnut former and including a follower adapted to engage said cam, said follower causing an operation of the doughnut former when passing each irregularity, a second shaft, an arm on said second shaft, an engaging member on said arm and adapted to engage a part movable with said follower to restrain engagement of the follower with the surface of said cam, a second cam on said first named shaft, and means operated by said second cam for periodically swinging said second named shaft to move said arm in a manner to cause the engaging member thereon to restrain movement of the follower when the follower is in a position to engage certain of the irregularities on said first named cam.

8. In a doughnut machine in which the doughnuts are progressed along a way, a doughnut former for depositing dough formations in the cooking liquid in the way, a drive shaft, a cam on the drive shaft, said cam having a plurality of depressions, a pivoted arm, a cam follower on said arm adapted to engage the cam and enter into said depressions, said follower causing an operation of the doughnut former when entering into each of said depressions, resilient means for swinging said arm to urge the follower into engagement with said cam, a second shaft, an arm on said second shaft, an engaging member on said second arm for engaging a part movable with said first named arm to hold said follower from engaging said cam when the follower is in a position to enter one of said depressions, a second cam on said first named shaft, an arm connected to said second named shaft and having a follower adapted to engage said second named cam, said second named cam having irregularities thereon for moving said arm when the first named follower is in position to enter into certain of the depressions in said first named cam.

9. In a doughnut machine in which the doughnuts are progressed along a way, a doughnut former for depositing dough formations in the cooking liquid in the way, a drive shaft, a cam on the drive shaft, said cam having a plurality of depressions, means controlled by said cam for

operating said doughnut former and including a pivoted arm, a follower on said arm adapted to engage said cam and to enter into said depressions, said follower causing an operation of the doughnut former when entering into each of said depressions, a spring, a spring housing enclosing said spring and pivoted to a part movable with said arm, said spring being seated against said spring housing and urging movement of said cam follower thereby, a lug on said spring housing, a second shaft, an arm carried by said second shaft, a hook on said arm adapted to engage said lug and prevent said spring from moving the spring follower into engagement with the cam, a second cam on said first named shaft, and means operated by said second cam for periodically swinging said second named shaft to cause the hook to engage the lug when the cam follower is in position to enter one of the depressions in said first named cam.

10. In a doughnut machine in which the doughnuts are progressed along a way, a doughnut former for depositing dough formations in the cooking liquid in the way, a drive shaft, a cam on the drive shaft, said cam having a plurality of depressions, means controlled by said cam for operating said doughnut former and including a pivoted arm, a follower on said arm adapted to engage said cam and to enter into said depressions, said follower causing an operation of the doughnut former when entering into each of said depressions, a spring, a spring housing enclosing said spring and pivoted to a part movable with said arm, said spring being seated against said spring housing and urging movement of said cam follower thereby, a lug on said spring housing, a second shaft, an arm carried by said second shaft, a hook on said arm adapted to engage said lug and prevent said spring from moving the spring follower into engagement with the cam, a second cam on said first named shaft, another arm on said second shaft, a cam follower on said second arm adapted to engage the second cam, said second cam being adapted to move said second shaft to cause the hook to engage the lug when the first named follower is in a position to enter one of the depressions in said first named cam.

11. In a doughnut machine in which the doughnuts are progressed along a way through the flow of the cooking liquid, a doughnut former for depositing dough formations in the cooking liquid, control means for controlling the number of doughnuts passing along said way, a drive shaft, a cam on said drive shaft, said cam having a plurality of irregularities, means controlled by said cam for operating said control device and including a follower adapted to engage said cam, and means for periodically engaging a part movable with said follower to restrain engagement of the follower with certain of said irregularities.

STEPHEN A. GARDNER.
